Invent.

H. B. McGOWAN

By Watson B. Coleman
Attorney

UNITED STATES PATENT OFFICE.

HENRY B. McGOWAN, OF HURLEY, OKLAHOMA.

WELL-DRILLING TOOL.

Application filed May 17, 1922. Serial No. 561,654.

To all whom it may concern:

Be it known that I, HENRY B. McGOWAN, a citizen of the United States, residing at Hurley, in the county of Cimarron and State of Oklahoma, have invented certain new and useful Improvements in Well-Drilling Tools, of which the following is a specification, reference being had to the accompanying drawings.

10 This invention relates to improvements in well drilling tools and more particularly to means for connecting the drill with its stem.

An important object of the invention is to provide means to prevent relative rotation of the drill and stem which is at the present time the common cause of losing the drill in the well, which always results in an expensive fishing operation.

20 A further object of the invention is to provide a device of this character which may be employed upon the drills and stems now in use without materially altering the construction thereof.

A still further object of the invention is 25 to provide a device of this character which is simple and durable in construction, efficient in its operation, and a general improvement in the art.

These and other objects I attain by the 30 construction and arrangement shown in the accompanying drawings wherein for the purpose of illustration is shown a preferred embodiment of my invention and wherein like reference characters designate like parts throughout.

In the drawings:—

Figure 1 is a side elevation showing a drill and stem connected in accordance with my invention;

40 Figure 2 is a vertical sectional view taken therethrough; and

Figure 3 is a section on the line 3—3 of Figure 2.

Referring now more particularly to the 45 drawings, the numeral 10 indicates a drill bit and 11 a threaded bit pin formed upon the shank 12 of the drill and adapted for engagement in a threaded socket 13 formed in the lower end of a stem 14.

50 In accordance with my invention the shank 12 of the bit is externally screw-threaded, as indicated at 15, with left-hand threads, the threads of the bit pin and bit pin socket being right-handed in the usual

construction. If these threads are left-handed, the shank is oppositely screw-threaded thereto, for a purpose presently to appear. The lower end of the stem has a portion thereof reduced upon the exterior to the inside diameter of the threads formed upon the shank of the bit, as indicated at 16, and the stem is provided at a point spaced thereabove with an annular key socket 17 adapted to receive therein an annular sectional collar 18. The numeral 19 designates a sleeve having an internal bore 20 of a size substantially equal to the outside diameter of the sectional collar 18 when assembled. At its upper end this bore is reduced to an opening 21 of the same diameter as the diameter of the stem 14, thereby forming a shoulder 22 adapted to abut against the upper face of the portions of the collar extending beyond the outer surface of the stem to limit the downward movement of the sleeve 19. The lower end of the sleeve is provided with an in-turned flange 23 having its inner face provided with screw-threads 24 adapted for coaction with the threads 15 of the shank 12.

In the use of my device the sleeve is slipped upon the end of the stem 14 until the opening 25 formed in the side wall thereof aligns with the collar groove 17. This opening is of sufficient size to permit insertion of the sections 18^a of the collar 18 therethrough so that they may be engaged in the groove. After the collar has been assembled in the groove the sleeve is moved upon the stem until the flanged portion 90 thereof is fully engaged with the reduced portion at the lower end of the stem thereof, exposing the lower end of the stem to permit engagement of the bit pin 11 in the socket 13 thereof. After the bit pin has 95 been fully engaged in the socket, the sleeve is moved downwardly until the threads of the flange 23 thereof are engaged with the threads 15 of the shank 12 and the sleeve threaded upon this shank until the binding movement of the shoulder 22 against the exposed face of the collar 18 prevents further rotation. It will be obvious that this binding action will tend to prevent any relative movement of the stem 14 and sleeve 19 and it will furthermore be obvious that the bit pin and shank being oppositely threaded, any tendency of the bit to rotate relatively to

the stem would tend to result in lengthening of the distance between the engaged portion of the sleeve and the collar 18, which tendency would be fully prevented by the key.

From the foregoing it is believed to be obvious that a coupling member constructed in accordance with my invention is particularly well adapted for the purpose for which it is intended for the reason that it may be readily applied to the bits and stems now in use and that it will prevent tendency of the bit and stem to separate. It will, of course, be understood that in the present construction of the bit and stems wherein the bit pin 11 is usually tapered and threaded, it requires but a slight relative rotation of the bit and stem to permit separation thereof. It will furthermore be obvious that the construction hereinbefore employed is capable of some change and modification without materially departing from the spirit of my invention and I accordingly do

not limit myself thereto except as herein-after claimed.

I claim:—

The combination with a bit having the pin and shank thereof oppositely screw-threaded, of a stem having a threaded socket receiving the pin, a sleeve having engagement with the stem limiting its upward movement thereon, securing means engaging the stem and insertible through an opening formed in the wall of the sleeve when the sleeve is in its uppermost position, said securing means when in engagement with the stem limiting the downward movement of the sleeve on the stem with the lower end of the sleeve extending below the lower end of the stem, the lower end of said sleeve having threads for engagement with the threads of the shank of the bit.

In testimony whereof I hereunto affix my signature.

HENRY B. McGOWAN.
